[57] **CLAIM**

The ornamental design for an asymmetric heat sink for electronic devices, substantially as shown and described.

DESCRIPTION

FIG. 1 is a perspective view of an asymmetric heat sink for electronic devices showing my new design; the broken lines being shown for illustrative purposes, only; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and FIG. 7 is a bottom plan view thereof.

FIG. 4

FIG. 5

FIG. 6

FIG. 7
